CLAIM

The ornamental design for a resilient flexible pull-tab, as shown and described.

DESCRIPTION

FIG. 1 is a perspective view of a pull-tab according to an exemplary embodiment of the present invention;

FIG. 2 is a side elevational view of the pull-tab shown in FIG. 1, wherein an opposing side elevational view of the pull-tab is substantially identical;

FIG. 3 is a top elevational view of the pull-tab shown in FIG. 1, wherein a bottom elevational view of the pull-tab is substantially identical;

FIG. 4 is a front elevational view of the pull-tab shown in FIG. 1;

FIG. 5 is a rear elevational view of the pull-tab shown in FIG. 1; and,

FIG. 6 is a perspective view of an alternate pull-tab according to another exemplary embodiment of the present invention.

The broken lines depicting portions of the resilient flexible pull-tab are for the purpose of illustrating environment and form no part of the claimed design.
